UNITED STATES PATENT OFFICE.

EDWARD B. CLARK, OF GOLCONDA, ILLINOIS.

STATION-INDICATOR.

1,282,541.

Specification of Letters Patent. Patented Oct. 22, 1918.

Application filed April 13, 1916. Serial No. 90,960.

To all whom it may concern:

Be it known that I, EDWARD B. CLARK, citizen of the United States, residing at Golconda, in the county of Pope and State of Illinois, have invented certain new and useful Improvements in Station-Indicators; and he does hereby declare that the following is a full, clear, and exact description of the invention, which will enable others skilled in the art to which it appertains to make and use the same.

This invention relates to station indicators. It relates more particularly to a cabinet for use on street cars or trains having therein an endless curtain or belt upon which the names of the various station stops are shown, certain mechanism being employed which is adapted to operate said curtain, either to indicate successively all stops or stations, or for indicating only important stations where limited trains stop.

An object of the invention is to furnish a station indicator for street railway cars or steam roads that can be used to indicate local stops or such stops as it may be the wish of the operator to show.

Another object is to furnish a station indicator that can be adjusted to indicate local or limited stops and which also can be reversed at will so as to be of use on trains running in either direction.

The invention, in addition to this, relates to certain details of construction and novel arrangements of parts as will be fully brought out herein.

In the appended drawing, forming a part of this application,

Figure 1 shows my station indicator in perspective.

Fig. 2 is a front elevation of the same on a larger scale with the front side removed. Fig. 3 is a side elevation of certain parts of the operating mechanism.

Fig. 4 is a side elevation of the cabinet.

Fig. 5 is a detail of a toothed belt; and, Fig. 6 is a horizontal section of certain parts of the cabinet and some of the operating mechanism.

A indicates the cabinet and B its front provided with a slot C through which extends an operating lever D.

E and F represent certain openings or windows in the front B through which to view the station names and other matter to be exhibited. G is an endless belt mounted upon rollers H supported in bearings in

the cabinet in any suitable manner, the shafts J upon which the rollers are mounted each carrying a pinion gear K with each of which meshes a gear L mounted upon shafts M.

Upon each of said shafts M, which are supported within the cabinet in any desired manner, is a wheel N over both of which extends a flexible belt O of suitable material, such as woven metal fabric or other non-stretchable material, provided on its outer surface with a series of extensions or teeth P which may lie between side walls Q whereby the teeth are inclosed except at their points.

The lever D, before mentioned, is mounted on a shaft D' within the casing, one of its ends being supported in a cross member D², for example, see Fig. 6. The inner end of said lever carries two pawls which are pivoted to it and are indicated by the letters S T, the pivot for the lever constituted by the shaft D' lying midway between the pivots of said pawls. A spring U bears upon the pawl T and constantly tends to move it in the direction of and into engagement with the belt O, while a spring V controls the pawl S for the same purpose. The said pawl S has an extended end W beyond its pivot and 2 is a cam secured on a shaft 3 which at its outer end extends through the wall of the cabinet, its inner end being seated in a socket 4 in the end of the said shaft D', a suitable key 5 holding said pin 90 in place, there being a finger piece 6 on said shaft 3 outside of the cabinet. The said cam is adapted when in one of its positions, as shown in full lines in Fig. 3, to engage the pawl T for moving it outward away from the belt. Likewise when in another position it is adapted to engage the extension of the pawl S and accomplish the same purpose while permitting the pawl T to engage the belt, it being the purpose, as may be seen, 100 to hold one or the other of the pawls out of engagement while the other is in use.

7 is a spring attached at one end to the lever D inside the cabinet, its other end being attached to the said cabinet, for example, the purpose of which is to hold the lever in its raised position, any suitable stop being used such, for instance, as the upper limit of the slot C in the front of the cabinet, to limit the raising movement.

8 indicates a series of holes in the end wall of the cabinet as shown in Figs. 1 and

4 in any one of which a pin 9 may be inserted to lie in the path of downward movement of the said lever D. 10 is a guide within the cabinet being mounted in any 5 suitable manner parallel to and behind one of the stretches of the belt O, said guide being supported in any suitable manner as by 11, for example, Figs. 2 and 3.

As has been stated in the objects, my purpose is to furnish a station indicator that 10 can be used to indicate local stops in successive order and which is reversible in its operation so as to be of use in either direction of travel of the train, and to convert 15 the same so that it may be used for limited stops, or so as to indicate only widely separated station stops, an adjustment in the cabinet being made to accomplish these purposes as will now be understood.

20 The movement of the lever D, which is always a downward one, will operate the belt or curtain G through the belt O by means of the pawls S T, the movement of the said belt O being in either direction according 25 to which pawl is in engagement with it, it being observed that since the pawls are located at opposite sides of the pivot (the shaft D') the downward movement of said lever will transmit movement in either direction to said belt O. The extent of movement imparted to the latter is according 30 to the particular adjustment of the pin 9 in the holes 8. For instance, if the said pin is in the highest hole 7 the limit of movement may be only such that each local stop 35 will be indicated in successive order. If it is desired to show limited stops opposite the window E the pin 9 may be adjusted to the proper hole, any one hole corresponding to 40 a given station, so that the operator, knowing this, shows the proper stop at the window.

It will be understood that by turning the finger piece the described cam 2 can be 45 moved to either of its two extreme positions, one of which will cause the curtain or belt G to travel in one direction, the other position causing the opposite direction of travel, the operator being thus provided with 50 means for the proper direction of movement of said curtain.

In order to have a considerable distance 55 of movement of the belt or curtain G with a small amount of travel of the pawls S T, the shafts J are preferably "geared up" by the use of the pinions K and the gears L already described. However, it is clear that a greater separation of the pivots of the pawls will also produce more movement of the 60 curtain G in a given movement of the lever D.

As an advertising feature the curtain or belt G may be provided opposite the names 65 of the station stops with names of hotels or business houses which may be brought

opposite the window F, as the station stop to which it corresponds comes opposite the window E. The advantage of being able to produce in a single device means by which local stops and limited stops may be shown 70 in either direction of travel will be appreciated.

The guide 10 acts as a firm backing for the belt O and receives the pressure of the latter due to the pressure of the pawls 75 thereon.

It is not my wish to be confined to the exact arrangement shown and described herein since there may be some very slight changes made that will still lie within the 80 meaning of the invention and the scope of the accompanying claims.

Having thus described my invention, I claim:

1. In a station indicator, the combination 85 of a traveling curtain or belt having station stops indicated thereon, means to operate it including an endless flexible traveling member, a lever pivotally mounted, a pawl pivoted to the lever at each side of the 90 pivot thereof, and separately adapted to engage and impart movement to the member in either direction, and means carried by the lever adapted to reverse the positions of the pawls whereby the direction of travel of 95 said curtain or belt may be reversed.

2. The combination in a station indicator, of a belt or curtain having station stops indicated thereon, of means to impart movement to the same including a traveling belt 100 provided with a series of teeth, a pivotally mounted lever, a pawl pivoted to the lever at each side of its pivot and each adapted to engage the said belt, means carried by the lever adapted to be moved to two different positions whereby to disengage one of the pawls from said belt and permit the other to engage, and a stop adapted to be placed in the path of movement of the lever for limiting the extent of that movement. 110

3. In a station indicator, the combination 115 of an endless belt having station stops indicated thereon, mechanism to carry and impart movement to said belt including a toothed belt, a pivotally mounted lever, a pawl pivoted thereto at each side of its point of support, each said pawl adapted to elastically engage said toothed belt, a guide to receive the latter against it, and means adapted to reverse the positions of the pawls 120 on the said toothed belt whereby to reverse the direction of its movement.

4. In a station indicator, the combination 125 of an endless belt having station stops indicated thereon, mechanism to carry and impart movement to said belt including a toothed belt, a pivotally mounted lever, a pawl pivoted thereto at each side of its point of support, each said pawl adapted to elastically engage said toothed belt, a guide 130

to receive the latter against it, means adapted to reverse the positions of the pawls whereby to reverse the direction of the movement of said belt, and a stop adjustable 5 to different positions adapted for limiting the extent of movement of said lever.

5. In a station indicator, the combination with a belt having a series of station stops indicated thereon, gearing to operate the 10 same including a pair of spaced wheels, a flexible member trained over said wheels, said flexible member including a series of equally spaced portions, a single lever pivotally mounted, a pair of pawls pivoted on

said lever, one at each side of the pivot of 15 said lever, said pawls adapted to separately engage the described spaced portions of the flexible member, and means engaging the pawls adapted to change the operative position of the same whereby in the movement 20 of the lever the described flexible member may be operated in either direction.

In testimony whereof I affix my signature, in presence of two witnesses.

EDWARD B. CLARK.
